UNITED STATES PATENT OFFICE.

CHARLES EDWARD POTTER, OF TORONTO, ONTARIO, CANADA.

PAPER CLIP.

Application filed October 6, 1922. Serial No. 592,826.

To all whom it may concern:

Be it known that I, CHARLES EDWARD POTTER, a citizen of the United States of America, and resident of the city of Toronto, 5 county of York, Province of Ontario, in the Dominion of Canada, have invented certain new and useful Improvements in Paper Clips, described in the following specification and illustrated in the accompanying 10 drawings, that form part of the same.

The principal object of this invention is to devise a paper clip which may be attached to papers and will pass through a typewriter holding such papers securely.

15 Further objects of this invention are, to facilitate the handling of papers in typewriters, effecting a saving of time for the typist and ensuring the holding of the carbon copies from slipping and becoming mis- 20 placed in relation to the original.

The principal feature of the invention consists in the novel formation of a strip of thin flexible material folded with a permanent crease adapted to receive and grip 25 papers inserted into the crease.

In the drawings, Figure 1 is a perspective view illustrating the manner of applying the clip to several sheets of paper.

Figure 2 is a perspective view showing the 30 clip in place holding the papers in a position ready for insertion into a typewriter.

Figure 3 is a cross sectional view through a clip showing the papers held therein.

In the making of carbon copies of type- 35 written papers it is extremely difficult for the typist to hold the various sheets in proper relative position when inserting them under the roller and even though the papers are properly placed, the sheets through the 40 action of the roller slip in relation to one another, consequently the carbon copies may be distorted and where some printed form

sheets are used it is practically impossible to place them in a typewriter so that the carbon impressions will be in alignment with 45 the printed material, no matter how carefully the original is manipulated.

This invention is of a very simple nature but accomplishes the desired result in a very effective manner and it consists of a sheet 50 1 of thin flexible material such as celluloid doubled longitudinally and set with a sharp crease 2.

The strength of the celluloid is such as to 55 very securely grip two sheets of paper and a carbon or more sheets as may be desired to hold the edges in true alignment and the clip being extremely thin and flexible adds no appreciable bulk and will bend quite readily around the typewriter cylinder and 60 in bending it will retain its secure grip of the papers.

The ends of the clip are arranged with a peculiar overlap, that is, the strip of material has its ends cut on the bias and when 65 the strip is folded the end edges 3 diverge so that one portion projects beyond the other, thus enabling the attachment of the clip to papers in a very simple manner as illustrated in Figure 1 of the drawings. 70

What I claim as my invention is:—

1. A paper clip, comprising, a strip of thin flexible resilient material folded longitudinally and permanently creased to receive and grip the paper sheets. 75

2. A paper clip, comprising a strip of celluloid doubled longitudinally and formed with a permanent crease.

3. A paper clip, comprising a strip of thin flexible resilient material folded intermediate of its width and at an oblique angle to the ends and formed with a permanent crease. 80

CHARLES EDWARD POTTER,
